UNITED STATES PATENT OFFICE.

DONALD L. COMPTON, OF AURORA, ILLINOIS.

POWDER BOX.

Application filed April 3, 1923. Serial No. 629,673.

This invention relates to box constructions, and more particularly boxes formed of pasteboard or the like, and especially designed for containing powder or other pulverized materials.

The primary object of the invention is to construct a box which will be exceptionally cheap to manufacture and one wherein it will be unnecessary to employ glue or other adhesive material to secure the ends of the walls of the box.

A further object of the invention is to provide means to prevent the material contained in the box, from passing between the contacting edges of the walls of the box.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a vertical sectional view through a box constructed in accordance with the invention.

Figure 2 is a view of the blank embodying the inner retaining section of the box.

Figure 3 discloses the inner box section in blank form, and

Figure 4 is a sectional view taken on line 4-4 of Figure 1.

Referring to the drawing in detail, the box includes a bottom section 5 and a cover section 6, which sections are identical in construction, and formed preferably of cardboard or the like material.

Positioned within the bottom section 5 is a rectangular section 7, which is of a width equal to the combined widths of the side walls of the bottom section 5 and cover section 6, as clearly shown by Figure 1 of the drawing.

The lining of the box is formed preferably of thin paper and is stamped or otherwise formed into a blank as indicated by Figure 3 of the drawing, the lining includ-

ing a bottom section 9 and side sections 10, each section 10 being provided with a lip 11 so that when the sides 10 are folded upwardly to conform to the contour of the box as shown by Figure 1 of the drawing, the lips may be bent downwardly over the upper edges of the sections 7 to secure the lining in position.

The lining retaining section is indicated generally by the reference character 12 and is stamped or otherwise conveniently formed from pasteboard of a ply equal with the ply of the section 7, the section 12 being also provided with side sections 13 that are formed with lips 14 that normally extend inwardly from the upper edges of the sections 13.

From the foregoing it will be seen that due to the construction as shown and described, I have provided a box which may be readily and easily stamped from pasteboard or the like material, and one wherein when the sections are assembled, provides a structure which will prevent the powder or other pulverized material from passing from the box at points between the bottom section and cover section, or between the adjacent ends of the side walls of the box.

What is claimed as new is:—

In a powder box, a rectangular body portion including a cover section and a bottom section of like construction, a rectangular inner section of a width equal to the combined widths of the cover section and bottom section, a lining of paper material fitted within the inner section and having side sections contacting with the inner section, lips at the ends of the side sections and bent over the upper ends of the inner section to hold the lining in position, said lips being held between the inner section and cover section, a lining retaining member having side sections engaging the side sections of the lining to hold the lining in position, and inwardly extended lips formed at the free ends of the side sections of the lining retaining member to guard the upper portion of the box.

In testimony that I claim the foregoing as my own, I have hereto affixed my signature.

DONALD L. COMPTON.
